CLAIM

The ornamental design for a fryer, as shown and described.

DESCRIPTION

FIG. 1 is a front view of a fryer showing the new design with the front door closed and the chutes in the open position. FIG. 2 is a rear view of the fryer with the rear door closed and the chutes in the open position.

FIG. 3 is a right side view of the fryer with the front and rear doors closed and the chutes in the open position.

FIG. 4 is a left side view with the front and rear doors closed and the chutes in the open position.

FIG. 5 is a front perspective view of the fryer with the front door closed and the chutes in the closed position.

FIG. 6 is a front perspective view of the fryer with the front door open and the chutes in the closed position.

FIG. 7 is a rear perspective view of the fryer with the rear door closed and the chutes in the closed position.

FIG. 8 is a rear perspective view of the fryer with the rear door open and the chutes in the closed position.

FIG. 9 is a rear perspective view of the fryer with the rear door closed and the chutes in the open position; and,

FIG. 10 is a rear perspective view of the fryer with the rear door open and the chutes in the open position.

(Continued)

The broken lines shown in the drawings depict portions of the fryer that form no part of the claimed design.
